[57] CLAIM

The ornamental design for an animal support, as shown and described.

DESCRIPTION

FIG. 1 is a front perspective view of an animal support showing my new design;

FIG. 2 is an end elevation view thereof, the opposite end thereof being identical thereto;

FIG. 3 is a front elevation view thereof;

FIG. 4 is a top plan view thereof; and,

FIG. 5 is a bottom plan view thereof.

FIGS. 1, 3, 4 and 5 are shown broken away to indicate indeterminate length.
